UNITED STATES PATENT OFFICE.

PHILIP AUGUSTUS JOHNSON, OF SPRINGFIELD, OREGON.

TELEPHONE ATTACHMENT.

1,130,608.

Specification of Letters Patent.

Patented Mar. 2, 1915.

Application filed November 12, 1912. Serial No. 730,843.

To all whom it may concern:

Be it known that I, PHILIP AUGUSTUS JOHNSON, a citizen of the United States, residing at Springfield, in the county of Lane and State of Oregon, have invented new and useful Improvements in Telephone Attachments, of which the following is a specification.

My present invention relates to a telephone attachment particularly adapted for use in connection with such apparatus forming a part of a subscriber's or intercommunicating system, where it is possible for a third party to overhear conversations transpiring between two parties.

The principal object of my invention is to provide means whereby such interloping, or attempt at eavesdropping may be detected audibly in such a manner that the particular apparatus from which the third party interferes, may be determined.

Further objects of my invention are to provide an attachment, embodying my invention, which may be easily installed in connection with existing telephone apparatus; and, such apparatus that is simple in construction and efficient in action.

A further object of my invention is to provide means whereby it is made necessary to maintain the attachment in a good working condition, in order to have the apparatus, to which it is attached, available for regular use.

Other objects of my invention will appear in the following detailed description, taken in connection with the accompanying drawings forming a part of this specification, and in which drawing:

Figure 1 is a compound view showing mechanism embodying my invention, parts being shown in elevation and section, and circuits diagrammatically indicated. Fig. 2 is a cross sectional view on the line 2-2 of Fig. 1. Fig. 3 is a perspective view of a switch used in connection with the line wires of the telephone system.

Similar characters refer to similar parts throughout the views.

In telephone systems of the aforesaid type, it is common practice to designate for each apparatus, a certain number of rings of constant or variable duration. For instance, one instrument may have designated therefor, one long and two short rings, another, one short and two long rings, another, one long, a short, and two long rings,

etc. Furthermore, each subscriber is furnished with a list of, or is familiar with the names of parties on the line, and the particular combination of rings for their particular apparatus. It is with the view of providing detection audibly, by a party, or parties, using the receivers, when another apparatus is rendered active by removal of the receiver from the hook thereof, and by producing sonorous vibrations by the receiver or receivers of the first mentioned apparatus, similar to the rings designating the latter apparatus.

Having the foregoing in view, the attachment comprises a movable element 4 for carrying a plurality of contacts 5 spaced apart from each other, as by insulation 6, and any number and length, according to the ring designating the particular apparatus to which it is attached. In the attachment as disclosed, it is designed for use in connection with telephone apparatus having designated thereto, the ring of one long, a short and two long. The element 4 has therefore, successive contacts 5 the first and latter two being longer than the second contact, as clearly shown in Fig. 1 of the drawing.

The element 4 is preferably revoluble with a spindle 7, carried by frame-work 8, to be disposed in a suitable housing, not shown in the drawings.

The usual receiver hook member 9 oscillatable about pivot 10 and receiver 11, normally carried thereby, of a telephone apparatus, are shown, and it is by movement of hook member 9, that movement of element 4 is controlled. This may be accomplished by mechanism designated generally by 12, which comprises an arm 13 rigid with hook member 9; a double arm lever 14, pivotally carried, in an insulated manner, by frame 8; a link 15 operatively connecting arm 13 and one arm of lever 14 to oscillate the latter by oscillation of hook member 9, and a pawl 15 movable with member 4, for engagement in a recess 16 in the other arm of lever 14. The lever 14 may be conveniently termed an escapement, since it permits the element 4 to make one complete revolution at each actuation of member 9.

The pawl 15 may be carried by a disk 17, rigid on spindle 7, so that when hook member 9 is down, the recessed arm of lever 14 is positioned in the path of movement of member 4, but allowing said latter member to move when hook member 9 is raised, and

the said arm of lever 14 moved out of the path of movement of pawl 15, all as clearly shown in Fig. 1 of the drawings.

As means for imparting movement to member 4 when freed by movement of mechanism 12, I provide a train of gears 18, including a main gear 19, actuated by a coil spring 20, of the type usually embodied in clock-work; and, a pinion 21 rigid with spindle 7 and which receives its movement from gear 19. The other gears and pinions shown, serve as a governor to prevent racing of gear 19. By this mechanism, the spring 20 must be periodically wound, it being understood that the spring expands as it becomes unwound.

For co-action with element 4 I provide a yieldable contact 22 which is disposed in the path of movement of contacts 5, this contact forming part of a circuit adapted to operate means 23 for providing a fluctuating current in the line conductors 24 and 25 of the telephone system. This means 23 preferably comprises a spark coil 26, including primary and secondary windings, a vibrator 27 being disposed in the circuit of the former; conductors 28 and 29 operatively connect with line conductors 24 and 25, respectively, the conductor 28 having a spark gap 30 therein. One lead of the primary winding of spark coil 26, is conductively connected as by conductor 31 in contact with metallic frame 8, with the member 4. The other lead is conductively connected with one pole of an electric generator 32, as by conductor 33, the other pole of said generator being conductively connected, to conductor 35, with yieldable contact 22, so that when contact 22 engages with one of the contacts 5, a complete circuit is provided through the primary winding of coil 26, causing fluctuations at gap 30 responsive to vibrator 27. It will be readily perceived, that the fluctuations at gap 30 will produce sonorous vibration by the diaphragms of the receivers off their hooks. It will be further perceived, that the duration of this sonorous vibration will be according to the length of time contact 22 engages with one of the contacts 5, and this engagement is dependent upon the length of such particular contact.

That the attachment must be maintained in a working condition in so far as mechanism 18 is concerned, I dispose a switch 36 in one of the line conductors (that designated 25), this switch being normally held closed, as by a spring 37. An arm 38 movably carried by frame 8, and insulated from said switch 36, in any suitable manner, extends so as to be actuated when spring 20 expands to a predetermined extent, the switch being opened by said actuation. Thus, as spring 20 is about to become weak in its ability to rotate gear 19, the switch 20 will be opened rendering the particular

apparatus with which the attachment is associated, inoperative, until the spring 20 is rewound, whereupon the said switch is closed responsive to action of spring 37.

The operation of the attachment is as follows: Assuming two parties are using the line conductors of the telephone system, and a third party removes the receiver, such as is shown in Fig. 1 of the drawing. This action allows hook member 9 to move upwardly, actuating escapement lever 14, and freeing member 4 to move responsive to mechanism 18. As soon as yieldable contact 22 engages with one of the contacts 5, a circuit is completed through the primary winding of coil 26, actuating vibrator 27. This complete circuit induces a current to be transmitted through conductors 28 and 29, with fluctuations at spark gap 30, responsive to actuation of vibrator 27. These fluctuations are very rapid, and continue until the element 4 moves so that contact 22 no longer engages with one of its contacts. In the example shown, the series of sonorous vibrations, produced through element 4, will be of one long one short and two long durations. Inasmuch as parties using the line conductors, have rendered their receivers operative, they can detect from the sonorous vibrations, the particular apparatus which has been rendered operative and available for interloping or eavesdropping.

Changes in details may be made without departing from the spirit or scope of my invention; but,

I claim:

1. In an apparatus of the character described, the combination with line conductors and a receiver hook member, of an element having a plurality of contacts, a second contact having engagement with contacts of said element, said element and second contact being movable one with respect to the other, a device for producing fluctuating current in said line conductors, operable upon completion of a circuit through any of the contacts of said element and said second contact, a windable spring motor for producing relative movement between said element and second contact when the said receiver hook member is moved in one direction, and means for breaking the circuit of said line conductors when said motor becomes unwound to a predetermined extent.

2. In an apparatus of the character described, the combination with line conductors and a receiver hook member, of an element having a plurality of contacts, a second contact for engagement with contacts of said element, said element and second contact being movable one with respect to the other, a device for producing fluctuating currents in said line conductors, operable upon completion of a circuit through any of the contacts of said element and said sec-

ond contact, a cut out switch in one of said line conductors, normally closed, coil spring operated means for producing movement of said element and second contact, one relative to the other, when said receiver hook is moved in one direction, and means operatively connected with said switch and co-operating with said coil spring to open said switch when said spring is unwound to a predetermined extent.

3. In an apparatus of the character described, the combination with line conductors and a receiver hook member, of a revoluble member having a plurality of contacts spaced apart from each other; a second contact for engagement with the said contacts of said revoluble member; a spark coil including primary and secondary windings, and a circuit breaker; an electric generator; means providing a circuit including said revoluble element, second contact, electric generator and the said primary winding of said spark coil; means having a spark gap conductively connecting the leads of the secondary winding of said spark with said line terminals; and, means effecting rotation of said revoluble element when said hook member is raised from a normal position.

4. In an apparatus of the character described, the combination with line conductors and a receiver hook member, of an element having a plurality of contacts; a second contact for engagement with contacts of said element, said element and second contact being movable one with respect to the other; a spark coil including primary and secondary windings, and, a circuit breaker; an electric generator; means pro-

viding a circuit including said element having a plurality of contacts, second contact, 40 electric generator and the said primary winding of said coil; means having a spark gap conductively connecting the leads of the said secondary winding of said spark coil with said line terminals; and, means effecting movement of said element and second contact, one relative to the other, when said receiver hook member is moved from a normal position.

5. In an apparatus of the character described, the combination with line conductors and a receiver-hook member, of a revolubly mounted element having a plurality of contacts, a motor for intermittently revolving said element, a pawl revoluble with 50 said element, an escapement member adapted to be actuated by removal and replacement of a receiver with respect to said receiver-hook member and mounted to operate coöperatively with said pawl and to free 55 said pawl for the revolution of said element through power derived from said motor upon the removal of the receiver from the hook, a second contact for engagement with the contact of said revoluble element upon 60 turning movement of the same, means for producing a current, and means to cause a fluctuation of said current in its passage as a circuit is completed through any one of 65 the contacts of said revoluble element and 70 said second contact.

PHILIP AUGUSTUS JOHNSON.
